UNITED STATES PATENT OFFICE.

THOMAS F. MOORE, OF SYRACUSE, NEW YORK, ASSIGNOR TO MOORE TRENCH MACHINE CO., OF SYRACUSE, NEW YORK, A CORPORATION OF NEW YORK.

LOADING-EXCAVATOR.

1,245,118.

Specification of Letters Patent. Patented Oct. 30, 1917.

Application filed April 8, 1916. Serial No. 89,985.

To all whom it may concern:

Be it known that I, THOMAS F. MOORE, a citizen of the United States of America, and resident of Syracuse, in the county of 5 Onondaga, in the State of New York, have invented new and useful Improvements in Loading-Excavators, of which the following, taken in connection with the accompanying drawings, is a full, clear, and exact 10 description.

This invention relates to certain improvements in loading-excavators or scraper-buckets for excavating and refilling trenches and similar work, and adapted to be used 15 more particularly in connection with overhead trestles and hoisting-and-conveying apparatus of the class set forth in my pending application, Serial No. 69,217, filed December 29, 1915, in which the back filling 20 proceeds simultaneously with the excavation so as to avoid as far as possible the dangers of "cave-ins," traffic obstructions and other objectionable factors accompanying the old method of piling the excavated 25 materials along the sides of the trenches.

Owing to the fact that these trenching operations are carried on very extensively in large cities and other districts where traffic is more or less congested, it becomes 30 necessary to restrict the width as far as may be consistent with efficient and economical work, and in most places requires that the walls of the trench be cut perpendicular and reinforced by sheathing and cross braces 35 or stays arranged at suitable intervals for retaining the sheathing in place, thus preventing movement of the walls of the trench.

Under such conditions, the available working space is extremely limited and prohibits 40 the use of many implements, such for example as a combined scraper and bucket permanently secured to each other.

The main object, therefore, of my present invention is to make the scraper and bucket 45 in separable units which are telescopically assembled and firmly interlocked with each other during the digging operation so as to load the bucket during such operation and permit the loaded bucket to be brought to 50 an upright position by a tilting movement relatively to the digger or scraper and

simultaneously disconnected therefrom preparatory to hoisting and conveying it along the superposed trestle to the rear of the excavation or other locality where it is 55 dumped.

Another object is to provide suitable power-operating means for manipulating the bucket into and out of the scraper and also for impelling the scraper along the 60 trench in either direction with or without the bucket therein.

A further object is to provide the scraper with suitable cutters for blocking out the load and defining the sides of the trench. 65

Other objects and uses relating to specific parts of the device will be brought out in the following description.

In the drawings—
Figure 1 is a top plan of a loading-excavator embodying the main features of my invention, a portion of the front top plate or hood being broken away to show the underlying plow points, and showing also the forward draft cables for the scraper 70 and bucket which are assembled for digging and loading.

Fig. 2 is a front end view of the device shown in Fig. 1, except that the draft cables are omitted.

Fig. 3 is a longitudinal vertical sectional view taken on line 3—3, Fig. 1, omitting the draft cable for the scraper and showing the rearward draft cables and connections for drawing the entire device backwardly and 85 tilting the loaded bucket to an upright position.

Fig. 4 is a side elevation of the same device showing the bucket as tilted to an upright position relatively to the scraper ready 90 for hoisting, the dotted lines above the bucket indicating its partially hoisted position, while the draft cable for the bucket is shown by dotted lines as detached therefrom to allow the attachment of the hoist- 95 ing cable thereto.

Fig. 5 is a side elevation of the same scraper and bucket, the front portion of the scraper being broken away, while the bucket is in position to be tilted downwardly 100 and forwardly to the position shown by dotted lines for telescoping interlocking con-

nection with the scraper as the bucket is drawn forwardly by its draft cable into the rear end of the scraper.

As illustrated, this loading-excavator comprises a scraper —1—, a bucket —2—, forward draft cables —3— and —4— for drawing the bucket into operative relation to the scraper and for drawing the scraper and bucket forwardly for filling the bucket, and a rearward draft cable —5— for tilting the loaded bucket to an upright position relatively to the scraper preparatory to hoisting, the cable —5— being also provided with a hook, as —6—, adapted to be connected to the rear end of the scraper for drawing the latter with or without the loaded bucket therein rearwardly.

The scraper and bucket are preferably made of sheet or rolled steel or other suitable metal capable of withstanding the strains and wear to which they are subjected, the scraper being provided with a substantially rectangular bottom —7— of somewhat greater length than that of the bucket to form a supporting platform therefor during the digging and loading operation, and is preferably formed integral with the opposite side plates, as —8—, which are of substantially the same length as the bottom, but are preferably L-shape and spaced a sufficient distance apart to receive the bucket between them, the portions of the sides at their junctions with the bottom being curved in cross section to correspond with the curved corners of the bucket.

The upright portions of the sides —8— rise from the front end of the bottom to a height substantially equal to or slightly greater than that of the bucket when the latter is supported upon said bottom, and are somewhat wider from front to rear than the vertical height of their remaining portions which extend rearwardly therefrom to the rear edge of the bottom.

The side plates —8— are provided with forwardly projecting fender plates —9— having their rear ends riveted or otherwise secured to the outer faces of the front ends of the plates —8— and their forward ends extending some distance beyond the front edge of the bottom to form fender plates for trimming the side walls of the trenches and deflecting the material into the bucket as it is loosened by the digging or plow points presently described.

The upper front edges of the fender plates —9— incline forwardly and downwardly from the upper front edges of the side plates —8— and are reinforced by angle irons —10— which in turn are connected by a cross plate or hood —11— and a front cross bar —12—, the ends of the latter being extended downwardly along the outer sides of the front ends of the fender plates —9— and

secured thereto by rivets —13— to reinforce the same.

The lower edges of the fender plates —9— are disposed in a plane above that of the bottom —7— and the front portions thereof are preferably inclined downwardly and rearwardly from their front ends to facilitate the trimming and finishing of the side walls of the trench by shearing cuts.

The top plate or hood —11— extends from the cross bar —12— rearwardly beyond the front edges of the plates —8— and serves to deflect the material which may be loosened by the scraper into the front open end of the bucket —2— when the latter is placed in operative position upon the scraper.

A reinforcing plate —14— of substantially the same width as the upright portions of the side plates —8— is rigidly secured by rivets or other suitable fastening means to the under side of the front end of the bottom —7— and extends some distance beyond the opposite longitudinal edges of said bottom and terminates in downwardly and outwardly deflected flanges —15—.

The lower edges of the rear ends of the fender plates —9— are extended downwardly and outwardly beyond the plane of the bottom —7— to form flanges —16— parallel with the flanges —15—, but spaced apart therefrom.

Suitable plow points or diggers —17— are interposed between and secured to the flanges —15— and —16— so as to stand edgewise in downwardly diverging planes at the corners of the bottom and sides of the scraper, their digging points being extended forwardly some distance beyond the front edge of the bottom for the purpose of blocking out the loose material and facilitating its entrance into the open end of the bucket as the whole device is drawn forwardly, these corner blades or diggers —17— also serving to block out and define the sides of the trench so as to provide ample clearance for the sides of both scraper and bucket and allow the latter to descend more readily to the bottom of the trench by their own weight.

Additional diggers or plow points —18— are provided with bifurcated rear ends fitted over and upon the front edge of the bottom —7— and reinforcing plate —14— and secured thereto by rivets —19—, said plow points —18— being preferably spaced uniform distances apart from each other and from the corner plow points —17— and are also provided with beveled front ends projecting forwardly some distance beyond the front edge of the bottom for loosening the earth or other material and facilitating its passage into the open end of the bucket.

The front ends of the angle irons —10— and overlying portions of the cross bar —12— are apertured for receiving pivotal bolts —20— to which are attached a pair 5 of clevises —21— for receiving the rear ends of the draft cables —4— by which the apparatus as a whole may be drawn forwardly for loosening the earth and loading it into the bucket.

Attached to the hook —6— is a clevis —22— adapted to be attached to the rear end of the scraper —7— by means of a pin —23— and provided with a bracket —24— for receiving and supporting a roller —25—.

This clevis, however, with the roller thereon is normally disconnected from the scraper so as to trail behind the same within easy reaching distance of the operator during the forward movement or digging and loading operation, but when it is desired to draw the scraper rearwardly by means of the cable —5—, the clevis is attached by means of the pin —23— to the rear end of the scraper with the roller directly under the center thereof, as shown more clearly in Fig. 3, thus preventing the rear end of the scraper from digging into the bottom of the trench.

The bucket —2— is of the "bottom-dump" type open at the top and substantially rectangular in cross section, except that its corners are rounded, the bottom, as —26—, being hinged at —27— to one side to swing outwardly and may be held in its closed position by any suitable form of latch —28— not necessary to herein illustrate or describe.

The interior of the bucket is divided by a central lengthwise partition —29— arranged in a plane at right angles to the axis of movement of the bottom and secured to the opposite walls of the bucket for bracing the same, the upper end of the partition being provided with apertured ears or lugs —30— for receiving a hook —31— on the end of the cable —3— by which the bucket is drawn into the scraper, and also for receiving a similar hook on a hoisting cable, as —32—, shown by dotted lines in Fig. 4.

The hinges —27— project outwardly beyond the corresponding side and bottom of the bucket and are adapted to drop into openings —33— in the bottom —7— of the scraper near the rear end thereof as the bucket is drawn on to said bottom with its front end in engagement with the rear edges of the diggers —18— so as to establish interlocking connection between the bucket as the latter is drawn forwardly by the scraper in the operation of digging and loading.

These coöperative interlocking connections, viz:—the hinge —27— and opening

—33— also serve as limiting stops to hold the bucket against undue rearward movement and to constitute a fulcrum therefor in the act of tilting the loaded bucket from a horizontal to an upright position, the latter being accomplished by means of a hook —34— on one end of the cable —5— in a manner presently described.

In operation, the empty bucket is lowered into the trench at a point just at the rear of the scraper or in a position similar to that shown in Fig. 5, whereupon the hook —31— of the cable —3— is attached to the ears —30— and the hook —34— of the cable —5— is also attached to the bucket in the manner shown in said figure. The cable —4— is then drawn forwardly by any suitable operating means, thereby tensioning the cable —3— and tilting the bucket forwardly and downwardly onto the bottom of the scraper, the continued forward movement of the cable serving to draw the bucket forwardly upon said bottom until its forward end encounters suitable stops, in this instance the rear ends of the diggers —18—, at which time the hinges —27— will have entered the openings —33—.

At the beginning of this operation of drawing the bucket onto the scraper, the cables —4— are slackened but are so adjusted as to be tensioned at about the same time that the forward end of the scraper engages the stops, so that the continued forward movement of the draft cable —4— places both the cables —3— and —4— under tension to exert a forward pull upon both the scraper and bucket.

This forward movement of the scraper with the empty bucket therein causes dirt or other material to be loosened and diverted into the bucket, such movement being continued until the bucket is filled, whereupon the cables —3— and —4— may be slackened and the cable —5— then wound upon a suitable engine-driven drum, not shown, for tilting the bucket right-side-up to the position shown in Fig. 4, the interlocking connections between the hinges —27— and openings —33— of the bottom of the scraper serving as a fulcrum about which the bucket is tilted to its upright position.

The hoisting cable —32— from the superposed traveling conveyer or other hoisting device is then lowered and hooked into the apertured ears —30— of the bucket, and the hoisting apparatus on said conveyer is then operated to raise the loaded bucket on to the conveyer to be carried to the backfill or other place of discharge, it being understood that before the bucket is hoisted the cable —5— is disconnected therefrom.

Before the bucket is hoisted and carried to place of discharge, an empty bucket may

be placed in the position shown in Fig. 5 and while the loaded bucket is being removed the empty bucket is drawn side-wise upon the scraper and the operation of 5 loading repeated in the manner described, thus permitting the work to be continued without material interruption.

This manner of attaching and detaching the bucket and scraper to constitute a unitary loading-excavator permits the use of 10 an ordinary bucket with a comparatively short scraper which may be manipulated in almost any trench, and at the same time permits either to be used independently of the 15 other if necessary, as for example in hand loading, in which case the plow will be simply used for loosening the material in the trench.

What I claim is:

20 1. In a loading excavator, the combination of a scraper and a bucket telescoping therewith with its open end facing forwardly, means for drawing the bucket end-wise along and upon the bottom of the 25 scraper, means on the scraper for limiting the forward movement of the bucket relatively to said scraper, and additional means for drawing the scraper with the bucket thereon forwardly.

30 2. In a loading excavator, the combination of a scraper and a bucket telescoping therewith with its open end facing forwardly, means for drawing the bucket end-wise along and upon the bottom of the 35 scraper, means on the scraper for limiting the forward movement of the bucket relatively to said scraper, additional means for drawing the scraper with the bucket thereon forwardly, interlocking connections be- 40 tween the lower rear edge of the bucket and scraper to form a fulcrum about which the bucket is tiltable upwardly and rearwardly, and means for tilting the bucket to an up-right position.

45 3. In a loading excavator, the combination of a scraper open at both ends, a bucket telescopically mounted on the bottom of the scraper with its open end facing forwardly, an opening in the bottom of the scraper near 50 the rear end thereof, a projection on the lower rear edge of the bucket entering said opening to hold the bucket against rearward displacement from the scraper during the scraping and loading operation, means 55 for drawing the bucket forwardly on to the scraper, additional means for drawing the scraper with the bucket thereon forwardly, and further means for tilting the loaded bucket upwardly and rearwardly to an up- 60 right position.

4. In a loading excavator, the combination of a scraper having outwardly and downwardly inclined digging teeth secured to the front ends of the corners thereof, a bucket

telescopically mounted in the scraper upon 65 the bottom thereof with its open end facing forwardly, means on the scraper at the rear of said digging points for limiting the forward movement of the bucket, additional means for limiting the rearward movement 70 of the bucket, and means for impelling the scraper with the bucket thereon forwardly for loading the bucket.

5. In a loading excavator, the combination of a scraper having outwardly and downwardly inclined digging teeth secured to the front ends of the corners thereof, a bucket telescopically mounted in the scraper upon 75 the bottom thereof with its open end facing forwardly, means on the scraper at the rear of said digging points for limiting the forward movement of the bucket, additional means for limiting the rearward movement 80 of the bucket, means for impelling the scraper with the bucket thereon forwardly for loading the bucket, and means for tilting the loaded bucket right-side-up preparatory to hoisting the same. 85

6. In an excavating and loading device, the combination with a digger and a receiver for the material, of a main draft cable for the digger and an auxiliary draft cable for drawing the receiver into position to be filled directly from the digger during the 90 digging operation. 95

7. In an excavating and loading device, the combination with a scraper and a separate bucket, of a main draft cable for the scraper and an auxiliary draft cable for the bucket attached to the main cable for drawing the bucket into position to be filled directly from the scraper during the digging 100 operation. 105

8. In an excavating and loading device, the combination with a digger and a receiver for the material of a main draft cable for the excavator, an auxiliary draft cable for drawing the receiver into position to be filled directly from the digger during the digging operation, and an additional cable for righting the loaded receiver relatively to the 110 digger. 115

9. In an excavating and loading device, the combination with a scraper and a separate bucket, of a main draft cable for the 115 scraper, an auxiliary draft cable for the bucket attached to the main draft cable for drawing the bucket into position to be filled directly from the scraper during the digging operation, and an additional cable for righting the loaded bucket relatively to the 120 scraper, said additional cable having means for attachment to the scraper for drawing the same in a direction opposite to that of the main cable. 125

10. In an excavating and loading device, the combination with a scraper and a separate bucket, of a main draft cable attached

to the scraper for drawing the same forwardly, an auxiliary cable attached to the bucket for drawing the same into position to be filled directly from the scraper during 5 the digging operation, an additional cable for righting the loaded bucket relatively to the scraper, a clevis attached to the additional cable and provided with means for attachment to the scraper whereby the latter 10 may be drawn rearwardly, and a roller

mounted on the clevis at the under side of the scraper when said clevis is attached thereto.

In witness whereof I have hereunto set my hand this 3d day of April, 1916.

THOS. F. MOORE.
